(57) **CLAIM**

The ornamental design for a clamshell container, as shown and described.

DESCRIPTION

FIG. 1 is a front perspective view of a first configuration of a first clamshell container embodiment;
FIG. 2 is a front elevation view of the first configuration of the first clamshell container embodiment of FIG. 1;
FIG. 3 is a rear elevation view of the first configuration of the first clamshell container embodiment of FIG. 1;
FIG. 4 is a left side elevation view of the first configuration of the first clamshell container embodiment of FIG. 1;
FIG. 5 is a right side elevation view of the first configuration of the first clamshell container embodiment of FIG. 1;
FIG. 6 is a top plan view of the first configuration of the first clamshell container embodiment of FIG. 1;
FIG. 7 is a bottom plan view of the first configuration of the first clamshell container embodiment of FIG. 1;
FIG. 8 is a perspective view of an alternate configuration of the first clamshell container embodiment of FIG. 1;
FIG. 9 is a front perspective view of a first configuration of a second clamshell container embodiment;
FIG. 10 is a front elevation view of the first configuration of the second clamshell container embodiment of FIG. 1;
FIG. 11 is a rear elevation view of the first configuration of the second clamshell container embodiment of FIG. 1;
FIG. 12 is a left side elevation view of the first configuration of the second clamshell container embodiment of FIG. 1;
FIG. 13 is a right side elevation view of the first configuration of the second clamshell container embodiment of FIG. 1;
FIG. 14 is a top plan view of the first configuration of the second clamshell container embodiment of FIG. 1;
FIG. 15 is a bottom plan view of the first configuration of the second clamshell container embodiment of FIG. 1; and,
FIG. 16 is a perspective view of an alternate configuration of the second clamshell container embodiment of FIG. 1. The stippled shading in the drawings indicates a contrast in appearance.

(Continued)

In the drawings, the broken line showing portions of a clamshell container depicts environment and forms no part of the claim. Alternating dashed-dot lines are boundary lines, the area within which is unclaimed and represented by dashed lines.
